UNITED STATES PATENT OFFICE

125,674

DESIGN FOR A DRESS

Betty Patterson Travis, Tarrytown, N. Y.

Application January 9, 1941, Serial No. 97,907

Term of patent 3½ years

To all whom it may concern:

Be it known that I, Betty Patterson Travis, a citizen of the United States, residing at 4 Glenwolde, Tarrytown, in the county of Westchester and State of New York, have invented a new, original, and ornamental Design for a Dress, of which the following is a specification, reference being had to the accompanying drawing, forming part thereof.

I claim:

The ornamental design for a dress, substantially as shown.

BETTY PATTERSON TRAVIS.
